SCALP MASSAGING APPARATUS

Konstanty W. Mierzejewski and Peggy I. Mierzejewski, Pottstown, Pa.

Application September 21, 1949, Serial No. 116,916.

4 Claims. (Cl. 128—48)

1

This invention relates to an apparatus for massaging the scalp of the human head and it consists in the constructions, arrangements and combinations herein described and claimed.

It is a cardinal object of the invention to provide a scalp massaging apparatus in which the scalp massaging element is formed in two sections, said sections being actuated through a suitable motor and lever members to effect a simultaneous forward and backward oscillatory movement along the scalp, the sections each having a multiplicity of elastic protuberances for contacting the scalp, thereby creating a circulation of blood through the scalp and effecting a soothing action on nerves thus contacted.

It is also an object of the invention to provide an elastic shield for association with the massaging sections and the protuberances thereof making the device highly sanitary in use.

It is a still further important object of the invention to provide a massaging element formed in two sections simultaneously oscillated, said sections being of such dimensions as to permit a person to move his or her head to desired points of contact with the massaging sections.

Additional objects, advantages and features of invention will be apparent from the following description considered in conjunction with the accompanying drawings; wherein

Figure 1 is a side elevation of the device in use;

Figure 2 is a fragmentary side elevation of the device with the side closure cover in open position to illustrate the drive means for the massaging sections;

Figure 3 is a horizontal section on the line 3—3 of Figure 2;

Figure 4 is a similar cross section on the line 4—4 of Figure 2;

Figure 5 is an elevational view of one of the massaging elements; and

Figure 6 is a cross section on the line 6—6 of Figure 5.

There is illustrated in Figure 1 a wheeled base 10 having an upright hollow support 11 which houses a vertically adjustable rack bar 12. The rack bar 12 is raised and lowered to position the housing 13 at desired heights, and in the present instance, this is accomplished by means of a gear 14 in mesh with the rack bar, a handle 15 actuating the gear.

The housing 13 includes a bottom wall 16, a rear wall 17 which is contiguous with respective end walls 18 which terminate at respective sides of the housing to form an opening 19 which is closed by a door 20, to permit access to the interior of the housing for repair or adjustment of parts of the mechanism as may be required.

2

The rack bar 12 has a fitting 21 at the upper end thereof for securement to the bottom wall 16 of the housing. The fitting 21 is internally threaded and receives a bolt 22 for securement of a frame member 23 extended horizontally of the bottom wall 16. The frame member 23 is additionally secured to the bottom wall by means of a transversely positioned strap 24, as best seen in Figures 2 and 4.

10 An upright standard 25 is secured on the horizontal frame 23 and is connected by a pair of vertically spaced horizontal straps 26 and 26'. A brace 27 is connected at one end to the strap 26, the other end being secured to the frame member 23 as shown in Figure 2. The brace 27 is angularly disposed between the frame 23 and the strap 26' to afford rigidity. A motor generally indicated at 28 is securely mounted upon the horizontal straps 26 and 26'.

The upright standard 25 has an upper threaded portion 29 and at the opposite end of the frame 23 an upright standard 30 is rigidly secured thereto, the upper end of which is formed with screw threads for reception of a nut 31 and the threaded portion 29 of the standard 25 is likewise provided with a nut 31', these nuts being positioned at corresponding heights. A top frame 32 suitably apertured to receive the threaded portions of the standards 25 and 30 is 20 positioned thereon and secured by respective nuts 33 and 33'. The frame 32 is positioned immediately above and aligned with the frame 23 affording support of a main drive shaft, as will be described.

25 Upon the frame 23 a transverse bar 34 is secured and a similar bar 35 is secured to the top frame 32, these bars being in horizontal alignment. Additionally, the frame 23 has a transverse bar 36 rigidly secured thereto and the top frame 32 is likewise provided with a rigidly secured bar 37. The bars 34 and bars 36 are braced by straps 38 and the bars 35 and 37 are similarly braced by straps 38'.

30 A main drive shaft 39 is journaled in suitable ball bearing housings 40 mounted in the frame 23 and top frame 32, the drive shaft having keyed thereto a pulley 41 in alignment with a pulley 42 of the motor 28. A belt 43 is trained about the pulleys 41 and 42 to effect the drive of the shaft. An additional pair of pulleys 44 and 45 are secured upon the shaft 39, being vertically spaced thereon and in alignment with respective pulleys 46 and 47 of respective shafts 48 and 49, which are suitably journaled between the bars 36 and 37 at respective ends thereof as best seen in Figures 2 and 4. A belt 40 is trained about pulleys 44 and 46 and a belt 51 is trained about pulleys 45 and 47. Under rotation of the shaft 39, the shafts 48 and 49 will rotate in a corresponding direction.

The shafts 48 and 49 project above the top frame 32 a suitable distance and upon each of the shafts an eccentric 52 is secured, and oscillatably mounted between the bars 34 and 35 respective shafts 53 and 54 are provided. The shafts 53 and 54 project above the bars 34 and 35, and have fixed thereon respective crank members 55. A pitman 56 is connected between respective eccentrics 52 and crank members 55, and it will be apparent that the shafts 53 and 54 will be oscillated in the same direction simultaneously.

The shafts 53 and 54 project below the bottom wall 16 of the housing and each has rigidly mounted on the lower end thereof a massaging element 57, attention being invited to Figures 5 and 6 of the drawings, wherein it will be seen that the massage elements are of hollow, substantially ovate formation which, when arranged in operative relation upon a human head will be spaced apart permitting movement relative to each other, and likewise, will permit the head to be moved to present a desired portion to a greater or lesser degree of massaging action at the option of the patient.

The massaging elements are preferably formed from a resilient material such as rubber and include a multiplicity of protuberances 58. The protuberances 58 project from the hollow portions of the elements and are of substantial lengths so that they may have a slight flexing action under movement of the massaging elements, the action thus simulating the movements of the human fingers of an operator, as customarily practiced.

In order to meet sanitary requirements, a shield 59 is employed consisting of a hollow cap member of a size to enclose the massaging elements and preferably has a peripheral edge 60 so constructed as to maintain the shield securely, yet removably upon the massage elements. The shield 59 has a like number of nipples 61 as there are protuberances 58 so that each of the latter will be encased by the nipples. The shields 59 may be removed from the massage elements for sterilization after use, and by reason of the fact that the massage elements are completely enclosed, insofar as contact with a person's head is concerned, liability of obtaining infections through repeated use is avoided.

However, the hollow cap member may be omitted and by virtue of a socket and set screw 53a the massage elements may be removed from the shaft 53 for sterilization.

In use, the massaging elements 57 are adjusted about a person's head, as shown in Figure 1, and the motor 28 is then energized through any suitable source of electric current. The belt 43 will rotate the shaft 39 which in turn will rotate the shafts 48 and 49, imparting motion of the pitman 56 which in turn will oscillate the cranks 55 thereby effecting simultaneous forward and backward movement of the massaging elements along the head of a patient.

While we have shown and described the structure specifically, this is by way of illustration only and we consider as our own all such modifications in construction as fairly fall within the scope of the appended claims.

What we claim:

1. In a massage device for a human head comprising a vertically supported horizontally disposed housing having a pair of spaced oscillatable shafts, means within the housing for oscillating said shafts, said shafts projecting outwardly of the housing and each shaft having a hollow ovate massaging element secured thereto adapted to

partly enclose the upper and lateral portions of a human head, said massaging elements being given a forward and backward movement under oscillation of the shafts, and each massaging element having a plurality of elongated flexible protuberances upon the hollow portion thereof.

2. In a massage device for a human head comprising a vertically supported horizontally disposed housing having a pair of spaced oscillatable shafts, means within the housing for oscillating the shafts, said shafts projecting outwardly and below said housing, and each shaft having a hollow ovate massaging element secured to the lower end thereof, the hollow portions of the massage elements being arranged in opposed relation and adapted to partly enclose the upper and side portions of a human head, said massage elements being given a forward and backward movement under oscillation of the shafts, and each massaging element having a plurality of elongated flexible protuberances upon the hollow portion thereof.

3. In a massage device for a human head comprising a vertically supported horizontally disposed housing having a pair of oscillatable shafts, means within the housing for oscillating the shafts, said shafts projecting outwardly and below said housing, each shaft having a hollow ovate massaging element secured to the lower end thereof, the hollow portions of the massage elements being arranged in opposed relation and adapted to partly enclose the upper and side portions of a human head, said massage elements being given a forward and backward movement under oscillation of the shafts, each massaging element having a plurality of elongated flexible protuberances upon the hollow portion thereof, and a shield device secured to each of said massage elements to enclose said protuberances.

4. In a massage device for a human head comprising a vertically supported horizontally disposed housing having a pair of oscillatable shafts, means within the housing for oscillating the shafts, said shafts projecting outwardly and below said housing, each shaft having a hollow ovate massaging element secured to the lower end thereof, the hollow portions of the massage elements being arranged in opposed relation and adapted to partly enclose the upper and side portions of a human head, said massage elements being given a forward and backward movement under oscillation of the shafts, each massaging element having a plurality of elongated flexible protuberances upon the hollow portion thereof, and an elastic shield secured to each of said massage elements having a peripheral edge for engaging about the contour of the massage elements and each shield having a nipple for enclosing respective protuberances.
